UNITED STATES PATENT OFFICE.

ROBERT H. BISHOP, OF HOLLOWAY ROAD, AND HENRY F. HAILES, OF HORNSEY, COUNTY OF MIDDLESEX, ASSIGNORS TO NETTLEFOLDS, (LIMITED,) OF BIRMINGHAM, ENGLAND.

SKATE.

SPECIFICATION forming part of Letters Patent No. 248,395, dated October 18, 1881.

Application filed May 20, 1881. (No model.) Patented in England December 9, 1880.

To all whom it may concern:

Be it known that we, ROBERT HODGES BISHOP, of Holloway Road, and HENRY FREDERICK HAILES, of Hornsey, both in the county 5 of Middlesex, England, have invented certain Improvements in the Construction of Skates, of which the following is a specification.

The object of this invention is to provide a skate which, having been previously adjusted 10 to fit the boot of the skater, may be instantly applied and firmly secured thereto, or be as readily disengaged therefrom when required.

In constructing a skate according to our invention we provide a fixed sole-plate for the 15 front part of the boot of the skater to rest upon, such fixed sole-plate being fitted with a toe piece or strap, and at its rear end with an adjustable gripping-piece. For the heel of the boot of the skater to rest upon we provide a 20 sliding heel-plate of peculiar construction. This heel-plate we forcibly thrust forward by means of a cam-headed locking-lever or its equivalent, so that by a single movement of the said cam-headed lever the front portion of 25 the boot will be thrust into the gripe of the toe piece or strap upon the fixed sole-plate, while at the same time the heel of the boot will be securely fixed between the adjustable gripping-piece on the rear end of the sole-plate and the 30 gripping-surfaces on the sliding heel-piece. We provide, moreover, a novel means for imparting to the said toe piece or strap an additional tightening up upon the boot of the skater in the act of applying the skate, by which means we 35 insure that the said toe piece or strap or straps shall be tightened up in proportion to the varying breadth of the boot to which the skate is applied. This we effect by the use of a lever arm or arms, to which the lower edges of 40 the strap or straps are riveted, the said lever-arms being drawn together by the forward movement of the heel-plate, operated by the cam-headed lever above described. We prefer- 45 ably employ two lever-arms, pivoted at their fore ends upon the same fulcrum-pin, their rear ends being curved or beveled off to engage with a V-shaped or forked projection on the front of the sliding heel-plate; but, if desired,

the lever-arms may be pivoted on separate but adjacent fulcrum-pins; or a single lever-arm may be used in conjunction with a fixed bar, such fixed bar serving the same purpose as a second movable arm. In this case the V-shaped termination or forked end of the heel-plate will be formed to correspond. 50

A skate constructed according to our invention and embodying these principles is shown in the accompanying drawings, wherein—

Figure 1 is a sectional side elevation, and Fig. 2 an inverted plan view, the blade of the 60 skate in the latter view being omitted for the sake of clearness.

In these figures, A is the blade; B, the fixed sole-plate, firmly secured to the blade by means of the bracket-piece C and a standard, C', carried by another bracket-piece, C''. The rear end of the sole-plate B overlies the front part of the heel-plate, and is slotted to allow of the longitudinal adjustment of the gripping-piece D, with which it is provided. This adjustable 65 gripping-piece D is furnished with prongs or a chisel-edge for entering the front of the heel of the boot, and when adjusted it is secured in place by the nut d.

E is the sliding heel-plate, of peculiar construction, whereby great strength is insured.

A plate of metal, e, preferably of circular form, as shown in Fig. 2, is formed of malleable cast or wrought iron, with vertical gripping-surfaces e' e', and is securely riveted to the under side of another plate of metal, e'', preferably stamped out of sheet-steel, by which method of construction a compound heel-plate of great strength is insured, as the vertical gripping-surfaces e' e' may be easily made of any required thickness. These plates e and e'' are slotted at f and g'', respectively, to allow of their sliding longitudinally over the bracket-piece C'', upon which the under plate, e, is kept down by a cheese-headed screw, or preferably by a screw, C⁴, and metal washer C⁵. The slot f in the plate e is narrower than the slot g'' in the plate e'', which overlies it, so that a strip of metal on each side of the slot f serves as a surface for the metal washer C⁵ to rest upon. 85 By this arrangement it will be seen that the 90

heel-plate E (composed of the two plates e and e') will be free to slide longitudinally on the bracket-piece C³, but will be prevented from rising therefrom by reason of the screw C⁴ and metal washer C⁵, above described.

In some cases we do not use a compound heel-plate, but simply bend down two tongues of metal, extending from the rear end of the heel-plate, and cause them to bear closely against the under side of the horizontal top of the bracket-piece C³. This is a simple and convenient method of construction when the metal of the heel-plate can be bent without fracturing. The gripping-surfaces e e' may similarly be formed by turning upward two broad tongues of metal at rear of the heel-plate.

The front portion of the compound sliding heel-plate E, above described, is slotted to allow of its passing the standard or upright C', above mentioned, which standard serves to keep the heel-plate steady and prevent lateral movement, and which also serves as a fulcrum-pin for the locking-lever F. The heel-plate E may also be conveniently slotted, as shown at d', to allow of its moving freely past the bolt, which serves, in conjunction with the nut d, to secure the adjustable gripping-piece D to the sole-plate B. The front of the heel-plate E is forked or spread out into the form of a V, (see e' e', Fig. 2,) and it is also furnished on its under side with a transverse flange or rib, e⁶, for the cam-headed locking-lever F to engage with. The forked extremity e' e' is covered by a strengthening-plate, x, as shown in Fig. 2, which strengthening-plate x may be conveniently turned down to form the rib e⁶.

G G are lever-arms, securely pivoted at g to the under side of the sole-plate B, and to these lever-arms the two sides of the leathern toe-strap H H are riveted. The free ends of these lever-arms G G are curved or beveled off, as shown at g' g', for the purpose of engaging with the forked or V-shaped termination e' e' of the sliding heel-plate E. It will thus be seen that on the heel-plate E being drawn back the lever-arms will be free to open and allow the toe-strap H H to expand, the better to receive the boot of the skater. The toe-strap may be made adjustable by laces or buckles, in the usual manner. When the sliding heel-plate E is forced forward by the cam-headed locking-lever F acting on the projecting flange or rib e⁶, formed by the turning down of the strengthening-plate x, the forked or V-shaped termination e' e' will engage with the curved or beveled ends g' g' of the lever-arms G G, and will forcibly draw the said arms together, thus tightening the toe-strap H H equably upon the boot of the skater. The gripping-surfaces e' e' will at the same time bear against the outer surface of the heel of the boot, and tightly press the front of the heel against the gripping-piece D, the boot of the skater being simultaneously thrust into the gripe of the toe-strap H H. The importance of this method of tightening the toe-strap upon the boot consists in the fact that

the said strap may be tightened exactly in proportion to the increasing breadth of the foot, instead of being contracted over the boot more at one portion than at another.

70

In Figs. 1 and 2 the shape of the cam-headed locking-lever F is clearly shown. The head of this lever is so shaped at h as to engage with a stud or stop, e⁶, formed on the under side of the heel-plate E, when the lever is placed at right angles to its locking position. On unlocking the lever this stud e⁶ will be caught by the curved part h of the lever, and the heel-plate will be thrust backward, as shown by the dotted position in Fig. 2. The lever F, when the skate is locked to the boot of the skater, will be snugly beneath the heel-plate, and will be secured in position by springing its tail end under a small catch, K, made fast to the bracket-piece C³ at the rear end of the blade.

75

If desired, the toe piece or strap H H may be simply riveted to the edges of the sole-plate, as it may be found that sufficient gripe on the boot may be obtained by the mere act of forcing the boot of the skater into the toe-strap H H by means of the cam-headed lever F.

80

It will also be obvious that, if desired, the blade of the skate may be made fast to the heel-plate, and that the sole-plate may be moved longitudinally by a cam-headed lever—such as F—suitably disposed to meet such a transposition of parts.

85

A hand-lever has been heretofore used for moving the sole-clamps and the heel-clamps of skates to secure the same upon the foot of the wearer. The existing constructions embodying such devices are defective in one or more particulars, either forming ineffectual modes of fastening or requiring complicated adjusting devices to secure proper action of the lever. We do not, therefore, broadly claim a skate so constructed; but,

90

Having now set forth the nature of our invention and explained the manner of carrying the same into effect, we wish it to be understood that we claim—

95

1. A skate constructed with a fixed sole-plate provided with a toe piece or strap and an adjustable gripping-piece, (such as D,) in combination with a sliding heel-plate, E, constructed and mounted substantially as herein shown and described, the said heel-plate E being operated by a cam-headed locking-lever, (such as F or its equivalent,) whereby the front of the boot of the skater may be forcibly thrust into the gripe of the toe-strap or its equivalent, the heel of the boot being at the same moment securely held between the gripping-pieces e', e', and D.

100

2. In a skate constructed and fixed to the boot in the manner specified above, the lever-arms G G, to which the edges of the toe piece or strap are attached, the said lever-arms being drawn together by the forward movement of the sliding heel-plate E, whereby additional tension is imparted to the said toe piece or

strap in the act of applying the skate, and the said toe piece or strap is tightened up or contracted in proportion to the varying breadth of the boot.

5 3. In a skate, the combination, with a fixed sole-plate and a lever arm or arms pivoted thereto, of a toe strap or straps, the said lever or levers operating to hold the forward portion of the foot firmly in place by imparting to a differential tension to the strap or straps

proportioned to the varying breadth of the boot to which said skate is applied, substantially as described.
